UNITED STATES PATENT OFFICE.

HAROLD D. ROSE, OF BROOKLYN, NEW YORK, ASSIGNOR TO MODEL BRASSIERE CO., OF NEW YORK, N. Y., A CORPORATION OF NEW YORK.

LADY'S UNDERGARMENT.

Application filed June 8, 1927. Serial No. 197,286.

The invention relates to undergarments and more particularly to ladies' undergarments of the confining type such as brassières, corset brassières, girdles and the like, and has for its object to provide such an undergarment of novel and distinctive structure and characteristics. The invention contemplates particularly the provision of an undergarment of the indicated class which 10 acts to flatten the human diaphragm, supports and restrains the abdomen by means of specially designed and located elastic gussets located along the top and bottom of an internal belt, controls the waistline and 15 avoids the usual unsightly bulging of the body, and confines surplus flesh of the lower figure without interfering with the freedom of movement of the wearer. The invention contemplates further a garment of the indicated class which gives to the bust the desired natural contour and corrects flatness and bulkiness at the indicated parts of the body. Other objects will appear from the 20 description hereinafter and the features of 25 novelty will be pointed out in the claims.

In the accompanying drawings, which illustrate an example of the invention without defining its limits, Fig. 1 is an inside face view of a confining garment embodying the novel features; Fig. 2 is an exterior view illustrating the garment as it appears when being worn, and Fig. 3 is an interior side view of the garment.

The garment itself comprises a main outer section which, in all cases, is constructed in accordance with the particular purpose for which the garment is designed and the class of confining undergarments to which said garment relates; in the illustrated example the main section is of the corset brassière type and consists of a front portion 10 and a rear portion 11, both portions being permanently connected at one end and at their opposite ends being provided with 40 cooperating fastening devices such as hooks and eyes 12 whereby the garment is removably fastened in place upon the wearer. The garment also may include shoulder straps 13 and other features commonly found therein 45 or especially incorporated in such garments.

The device which comprises the invention consists of a belt located upon the inside of the main outer section of the garment and arranged to surround the human body internally of said main section when the garment

is being worn. The belt consists of a major section 14 and a minor section 15, each having one end secured in the garment, preferably in the rear portion 11 of the outer section by stitching A as shown in Fig. 1. At 60 their opposite free ends the belt sections 14 and 15 are provided with cooperating fastening devices such as hooks and eyes 16 capable of being detachably connected with each other for detachably fastening said belt 65 in place about the human body. The major section 14 of the belt has its upper edge curved as indicated at 17 toward an upwardly projecting portion 18 located at an intermediate point of said section 14 as shown 70 in Fig. 1. Upon opposite sides of said upward projection 18 the belt section 14 is provided with inserted elastic gussets 19 of downwardly tapering form and terminating at intermediate points of said belt section 14. 75 The latter is further provided with additional elastic gussets 20 projecting upwardly from the lower edge thereof and terminating at a distance from the apices of the gussets 19. The gussets 20 are located in 80 approximate registry with the gussets 19 and converge upwardly toward their upper edges which preferably are cut along inclined lines 21 as illustrated in Fig. 1. The belt sections 14 and 15 may further each be 85 provided with elastic inserts 22 extending vertically across said belt sections throughout the vertical width thereof. In the preferred arrangement bones or other stiffening devices 23 are located in the belt section 14 90 in registry with the projecting portion 18 and additional bones 24 may be located in said belt section 14 upon opposite sides of the bones 23 if desired.

The garment is worn in the customary 95 manner and the belt sections are secured in place about the body of the wearer by connecting the fastening devices 16 with each other, after which the fastening devices 12 may be connected together to fasten the 100 outer main section of the garment in place. When in position upon the person, the upward projection 18 of the internal belt extends between the busts of the wearer with the curved upper edge 17 of the belt section 105 14 lying below the same as will be clear from the illustration in Fig. 2. The action of the gussets 19 and 20 is such that the belt will be comfortably anchored close to the body and maintained in the diaphragm in a flat- 110

tened condition at all times regardless of whether the wearer assumes sitting or standing positions. The gussets 19 and 20 are specially designed to act as supports and to restrain the abdomen without discomfort to the wearer. The garment furthermore controls the waistline perfectly and does away with customary unsightly bulges which are oftentimes present with existing garments.

10 The novel confining garment furthermore acts upon the thighs and confines any surplus flesh of the lower figure while at the same time permitting absolute freedom of movement. In addition, the garment gives 15 a middle contour to the busts and corrects unstylishness and undesirable flatness or bulkiness.

While the invention is illustrated and described with respect to a confining garment 20 of the corset brassière type, it is to be understood that it may be used with equal efficiency in connection with confining garments of other types such as brassières, girdles and the like.

25 Various changes in the specific form shown and described may be made within the scope of the claims without departing from the spirit of the invention.

I claim:

30 1. In a confining garment of the kind described, the combination of a main outer section adapted to be detachably secured upon the wearer, a belt located upon the inside of said main section and arranged to surround 35 the human body interiorly of said main section, said belt comprising a major section and a minor section, each having one end secured to the outer section, a single set of fastening devices for detachably fastening said 40 belt in place about the human body, the major belt section being provided with an upward projection extending between the busts and having its upper edge curved in opposite directions from said projection, a pair 45 of V-shaped elastic gussets in said major belt section projecting downwardly from the upper edge thereof at opposite sides of said

upward projection at points equidistant therefrom and having their apices located at intermediate points of said main section, and 50 a pair of additional elastic gussets in said major belt section converging upwardly from the lower edge thereof and having their upper edges at a distance from the apices of said V-shaped gussets, the said upper inner edges diverging upwardly and away from the vertical center line of said major belt section.

2. In a confining garment of the kind described, the combination of a main outer section adapted to be detachably secured upon the wearer, a belt located upon the inside of said main section and arranged to surround the human body interiorly of said main section, said belt comprising a major section 65 and a minor section, said sections having one end secured to the outer section, a single set of fastening devices for detachably fastening said belt in place about the human body, the major belt section being provided with an upward projection extending between the busts and having its upper edge curved in opposite directions from said projection, a pair of V-shaped elastic gussets in said major belt section projecting down- 70 wardly from the upper edge thereof at opposite sides of said upward projection at points equidistant therefrom and having their apices located at intermediate points of said main section, and a pair of additional 75 elastic gussets in said major belt section converging upwardly from the lower edge thereof in registry with said V-shaped gussets and having their upper edges at a distance from the apices of said V-shaped gussets and extending along inclined lines, and 80 elastic inserts in both of said belt sections extending throughout the vertical width thereof near the attached ends of said sections.

45 In testimony whereof I have hereunto set my hand.

HAROLD D. ROSE.
